UNITED STATES PATENT OFFICE.

HANS EJNAR RASMUSSEN, OF GRAETTINGER, IOWA.

TROUSERS HOLDER AND PRESS.

Application filed April 18, 1922. Serial No. 555,109.

To all whom it may concern:

Be it known that I, HANS EJNAR RASMUSSEN, a subject of the King of Denmark, and resident of Graettinger, Palo Alto 5 County, Iowa, have invented a new and useful Trousers Holder and Press, of which the following is a specification.

An object of this invention is to provide an improved tool adapted for use in pressing 10 clothing, more particularly trousers.

A further object of this invention is to provide for folding a clothes-pressing tool on a line transversely of the device, for convenience in packing and transportation.

15 A further object of this invention is to provide improved means for moving a clamping bar through an arc on an axis parallel with the trend of the body of the tool.

A further object of this invention is to 20 provide foldable means adapted to simultaneously clamp and crease opposing margins of an object being treated.

25 My invention consists in the construction, arrangement and combination of elements hereinafter set forth, pointed out in my claims and illustrated by the accompanying drawings, in which—

Figure 1 is a plan and Figure 2 a side elevation of my improved device; the dotted lines in Figure 1 showing positions assumed by the clamping bars at times and the dotted lines in Figure 2 indicating a folded position of the device adapting it for convenient transportation and storage. Figure 3 is an end elevation of the device in closed position. Figure 4 is a detail vertical section on the indicated line 4—4 of Figure 1.

In the construction of the device as shown 30 the numerals 10, 11, 12 designate base members which preferably are arranged parallel with each other and spaced apart and are substantially alike in size and construction. Each of the base members is formed with a longitudinal slot 13 (dotted lines Figure 1). 35 Two pressing clamps A, B of foldable character are provided and arranged substantially parallel on and transversely of the base members 10, 11, 12. The pressing clamps are alike in construction and are arranged oppositely and respectively spaced from end portions of the base members, one of said clamps extending transversely of the slots 13. Each pressing clamp preferably

is formed of upper and lower sections and 55 said sections each comprise similar plates or bars; the several plates or bars of a given clamp being designated by the numerals 14, 15, 16 and 17. The plate or bar 14 of the clamp A is fixed between its ends to the base member 10 and the plate or bar 15 of said clamp is fixed between its ends to the base members 11 and 12. The plates 14 and 15 60 are not directly connected. The plate or bar 16 is hinged at its outer margin to the plate or bar 14; and the plate or bar 17 is hinged at its outer margin to the plate or bar 15. The plates 16, 17 are directly connected by a hinge 18 articulating on an axis transversely 65 of the trend of the clamp A somewhat contiguous to the transverse plane of the base member 11. The plate or bar 14 of the clamp B is connected to the base member 10 by a screw 19 seated in said plate and extending loosely and slidably through the slot 13. The plate or bar 15 of the clamp B is secured to 70 the base members 11, 12 by screws 20 seated therein and extending loosely and slidably through the slots 13 in said base members. The plates 14, 15 of the clamp B are not 75 directly connected. The plate 16 of the clamp B is hinged at its outer margin to the plate 14 beneath it and the plate 17 of said clamp is hinged at its outer margin to the plate 15 beneath it. The plates 16, 17 of the clamp B are connected by a hinge 21 articulating on an axis alining with the axis of the hinge 18. The clamp B is movable toward 80 and away from the clamp A by reason of the sliding connection between the screws 19, 20 and the base members, thus compensating 85 for different widths of articles to be received in the clamps conjunctively. Likewise it is convenient to arrange the clamps A and B in somewhat diverging planes because of the sliding connection between the clamp B 90 and base members, to accommodate tapering forms of objects to be pressed. Resilient blocks 22, 23, 24 are provided and one of them is mounted on one end portion of each 95 of the base members 10, 11, 12, and said blocks are normally of slightly greater thickness than the outer margin of the clamp A. Bolts 25, 26, 27 are mounted through end portions of the base members 10, 11, 12 and 100 the resilient blocks 22, 23, 24 respectively and are provided with wing nuts on their 105

upper end portions. Clamping bars 28, 29, 30 are pivoted at one end each on the respective bolts 25, 26, 27 and are adapted to be clamped on and compress the resilient blocks by means of the wing nuts. The clamping bars 28, 29, 30 are adapted to extend across the clamps A and B and are formed with laterally opening notches 31 in their outer ends, which notches are adapted to receive bolts 32, 33, 34 mounted through and rising from opposite end portions of the base members 10, 11, 12 respectively, the latter bolts also being provided with wing nuts. The bolt 26, being the central one of the series, preferably is jointed and adapted for articulation between its ends, the joint thereof being contained in the resilient block 23, which block preferably is made of india rubber.

In practical use the clamping bars 28, 29, 30 may be moved into the positions shown by dotted lines in Figure 1 by first moving them on arcs horizontally to release them from the bolts 32, 33, 34; the bars 28 and 30 being continued in horizontal movement through one hundred eighty degrees, if desired, and the bar 29 being continued through an arc of one hundred eighty degrees on the axis of articulation of the bolt 26. Such provision is made because of a limitation of horizontal movement of the bar 29 occasioned by the contiguity of the bars 28 and 30 thereto. The plates 16, 17 may be turned upwardly on the hinge connections with the plates 14, 15 and a garment, such as trousers (dotted lines interior of Fig. 1) may be folded and arranged with side margins of the legs thereof in recumbent positions on the lower elements of the clamps. Then the upper elements of the clamps may be closed upon the side margins of the garment and caused to engage therewith and then the clamping bars 28, 29, 30 may be replaced across the clamps A and B and be compressed thereon and in turn compress the members of the clamps together by manipulation of the wing nuts on the bolts 32, 33, 34. The garment may be allowed to remain in the tool and under the compressing influence thereof any desired time to the end that the creases may be formed in the marginal portions of the legs of the garment. During the operation of locating and securing the garment in the clamps the manipulator may stretch, straighten and arrange to shape the legs of the garment so that the operation of pressing the creases therein may also effect a desired restoration of form thereto.

When the tool is not being employed for pressing purposes it may be closed and secured in closed position and then be folded by articulation of the hinges 18 and 21 into compact form of materially less length than

its normal length in use, thus facilitating storage and transportation of the tool.

65

I claim as my invention—

1. A trousers holder and press, comprising base members, a clamp fixed thereto, a clamp slidably mounted on the base members substantially parallel with the first clamp, clamping bars pivoted to the base members and adapted to overlie both clamps, and means for clamping the bars on said clamps.

2. A trousers holder and press, comprising base members, a clamp fixed thereto, a clamp slidably mounted on the base members substantially parallel with the first clamp, clamping bars pivoted to the base members and adapted to overlie both clamps, and means for clamping the bars on said clamps, said clamps being formed in sections hinged together and adapted to articulate on a line transversely of the clamps.

3. A trousers holder and press, comprising spaced base members each formed with a longitudinal slot, clamp members extending transversely of and fixed to said base members, clamp members hinged to the first clamp members, other clamp members slidably connected to said base members, and further clamp members hinged to said other clamp members, bars pivoted to the base members and adapted to extend across both clamps, and means for clamping said bars toward said base members.

4. A trousers holder and press, comprising spaced base members each formed with a longitudinal slot, clamp members extending transversely of and fixed to said base members, clamp members hinged to the first clamp members, and hinged together, other clamp members slidably connected to said base members, further clamp members hinged to said other clamp members and hinged together, bars pivoted to the base members and adapted to extend across both clamps, and means for clamping said bars toward said base members.

5. In a trousers holder and press, a base member, clamps thereon, resilient blocks on the base members, clamping bars pivoted on said blocks and adapted to extend across the clamps, and clamping devices connecting the opposite ends of the base members and bars.

6. In a trousers holder and press, a base member, a resilient block on one end thereof, a jointed bolt extending through said base member and block, a clamping bar pivoted on said bolt, and a wing nut on said bolt confining said bar to said block.

Signed at Graettinger, in the county of Palo Alto and State of Iowa, this 12 day of January, 1922.

HANS EJNAR RASMUSSEN.
